UNITED STATES PATENT OFFICE.

ERIC W. PALMQUIST AND GEORGE G. FLOYD, OF ST. LOUIS, MISSOURI,
ASSIGNORS TO THE SHICKLE, HARRISON & HOWARD IRON COMPANY,
OF SAME PLACE.

CAR-TRUCK.

SPECIFICATION forming part of Letters Patent No. 651,117, dated June 5, 1900.

Application filed September 11, 1899. Serial No. 730,125. (No model.)

To all whom it may concern:

Be it known that we, ERIC W. PALMQUIST and GEORGE G. FLOYD, citizens of the United States, and residents of the city of St. Louis, 5 in the State of Missouri, have invented certain new and useful Improvements in Car-Trucks, of which the following is a full, clear, and exact description, reference being had to the accompanying drawings, forming part of 10 this specification.

Our invention relates to that class of car-trucks wherein provision is made for removing the axles and journal-boxes in a direction lengthwise of the side frame. It has heretofore been proposed to so construct the ends 15 of the side frames as to permit the axles, with the wheels, of course, and the journal-boxes to be removed without having to raise the frames vertically until they clear the axle-boxes—as, for instance, in Figure I of Patent No. 604,608, dated May 24, 1898, removable bolts 15, that form the outer ends of the side frames, are provided for this purpose, so that by removing the bolts and jacking up 20 the side frames until the pressure on the axle-boxes is relieved the axles and boxes may be removed in the direction lengthwise of the side frames, whereas with the construction shown in Fig. IV of said patent the side 25 frames would have to be jacked up until they would clear the axle-boxes before the latter can be removed.

The object of our invention is to provide a strong, durable, and effective construction of 30 the class stated and one which is not liable to get out of order or to be rendered unsafe by use.

Our invention consists in features of novelty hereinafter fully described, and pointed 40 out in the claims.

Fig. I is a detail side view illustrative of our invention. Fig. II is a front view of the retaining-bar, part of the end of the side frame being shown, the bar not being elevated to its raised position or the position it occupies when in use. Fig. III is an enlarged detail sectional view taken on line III—III, 45 Fig. II, the retaining-bar being shown in its elevated position. Fig. IV is a perspective 50 view of the retaining-bar. Fig. V is a detail

top view of the lower arm of the side frame. Fig. VI is a perspective view of the washer. Figs. VII to X, inclusive, represent a modification, Fig. VII being a side view, Fig. VIII a top view of the upper arm of the side frame, 55 Fig. IX a perspective view of the retaining-bar, and Fig. X a vertical section taken through the arms of the side frame and through the retaining-bar and washer. Figs. XI to XIV, inclusive, represent a second 60 modification, Fig. XI being a side view, Fig. XII a perspective view of the upper arm of the side frame and the upper end of the retaining-bar and washer, Fig. XIII a top view of the lower arm of the side frame, and Fig. 65 XIV a perspective view of one of the washers used in the modification.

Referring to the drawings, 1 represents part of one of the side frames of a car-truck—such, for instance, as is shown in the patent referred to. Each end of the side frame has an upper integral arm 2 and a lower integral arm 3, between which the axle-box 4 and the axle-box spring 5 are located. The box is retained in place by a bar or frame 6 (illustrated 70 in Fig. IV) and which, as shown, consists of a back 6^a, parallel side members 7, a top 8, and a bottom 9. Extending upwardly from the top 8 are flanges 10, and extending downwardly from the bottom 9 are flanges 11. The 75 upper arm 2 of the frame is provided with a shoulder 12, (clearly illustrated in Fig. III,) and the lower arm of the frame is provided with shoulders 13. (See Fig. V.)

When the axle-box and spring have been 80 placed in position, the bar 6 is placed with its lower end over the arm 3 of the frame, the flanges 11 straddling the arm behind the shoulders 13. Being moved to a vertical position, the bar is now raised until its flanges 10 straddle the upper arm of the frame behind the shoulder 12, as shown in Fig. III. A washer 85 14 is now inserted between the bottom of the bar and the upper face of the arm 3 of the frame and acts to hold the bar in its elevated 90 position, and a bolt 15 is inserted through perforations formed in the bottom of the bar, the washer, and in the outer end of the arm 3 to hold the washer in position. The bar is thus 95 firmly held in place without any strain being 100

exerted on the bolt or any removable part of the structure, the strain being entirely taken up by the flanges 10 and 11 and the shoulders 12 and 13, which form integral parts of the structure, so that there is no liability of the displacement of any part which would allow the bar to become loose or unanchored, and thus accidental release of the axle-boxes is impossible.

- 10 If desired, a bolt 16 may be passed through the upper end of the retaining-bar and the outer end of the arm 2, as shown in Figs. I and III, to take up any slight play that might exist, and thus prevent any rattling of the parts.
- 15 To prevent the bolt 16 from dropping out should the nut become loose and to avoid any possibility of the bolt 15 jumping out should its nut come off, we insert transverse pins 17 through the bar 6, close against the 20 ends of these bolts.

In Figs. VII to X, inclusive, we have shown a modification wherein a single bolt 18 is employed in lieu of the bolts 15 and 16, and inasmuch as this long bolt cannot, in some instances, be removed in a vertical direction 25 on account of coming against the car-body we form a slot 20 in the outer end of the arm 2 of the side frame and provide vertical flanges 21, between which the head of the bolt fits, so that when the axle-boxes are to be removed 30 it is simply necessary to raise the bolt 18 until the washer 14 is released, and then by taking out the washer and allowing the retaining-bar to drop to release its upper end the bar and 35 bolt can be taken out together. Inasmuch as the ends of the arms of the truck-frame and the retaining-bar are the same (with the noted exception of the slot 20 and the flanges 21) in this modification as in the preferred 40 construction, we have given the parts the same reference-numerals.

In Figs. XI to XIV, inclusive, we have shown another modification. In this modification the retaining-bar is of the same shape as in 45 the other two constructions. The upper end or arm of the side frame is, however, formed with a slot to receive a downwardly-extending lug 22 on a washer 23, and the arm is further provided with shoulders 24, behind which 50 the washer 23 fits. When the parts are in position, the lug 22 engages the upper end of the retainer-bar, as shown in Fig. XI, and this holds the bar from outward movement, while it is held from lateral movement by its flanges 55 10 engaging the outer end of the arm, as in the preferred construction. The lower arm is also formed with a slot 24 to receive an upwardly-projecting lug 25 on a washer 26, this lug engaging the lower end of the retaining-bar, thus holding this end of the bar from outward movement, while lateral movement of this end of the bar is prevented by the flanges 11 engaging the end of the side frame, as in the preferred construction. The lower 60 arm is also provided with a shoulder 28, behind which the washer 26 fits. In this lat-

ter modification a bolt 27 is employed that passes through the washers 23 and 26 and through the retaining-bar, as illustrated in Fig. XI. While in this latter modification a bolt is depended upon through the medium of the washers 23 and 26 and their lugs 22 and 25 to hold the retaining-bar from outward movement, yet the lateral movement of the bar is prevented by its flanges engaging the 75 arms, so that to the extent of preventing lateral movement of the bar the bar and arms are self-acting and do not depend upon a bolt or any removable part of the structure to prevent this movement, and to this extent our 80 invention is embodied in this modification in the same manner as in the preferred form of construction.

We claim as our invention—

1. In a car-truck, the combination of a side 85 truck-frame, upper and lower arms integral with said side truck-frame and between which the axle-box fits, and a retaining-bar fitted between said arms and overlapping and engaging therewith in both directions transverse 90 to its length; substantially as set forth.

2. In a car-truck, the combination of a side frame having upper and lower integral arms between which the axle-box is adapted to fit, and a retaining-bar adapted to fit between 95 said arms and having vertical flanges engaging the arms; said arms having shoulders behind which the bar fits, substantially as set forth.

3. In a car-truck, the combination of a side 100 frame having upper and lower integral arms provided with integral shoulders and between which the axle-box is adapted to fit, and a retaining-bar adapted to fit between said arms and having integral flanges engaging said 105 arms, substantially as set forth.

4. In a car-truck, the combination of a side 110 frame having upper and lower arms provided with shoulders and between which the axle-box is adapted to fit, a retaining-bar adapted 110 to fit between said arms and having vertical flanges adapted to engage said arms, and a washer for holding said bar in its elevated position, substantially as set forth.

5. In a car-truck, the combination of a side 115 frame having upper and lower arms between which the axle-box is adapted to fit and which are provided with shoulders, a retaining-bar adapted to fit between said arms and having flanges engaging said arms, a washer for holding 120 said bar in its elevated position, and a bolt for holding said washer in position, substantially as set forth.

6. In a car-truck, the combination of a side 125 frame having upper and lower arms provided with shoulders and between which the axle-box is adapted to fit, a retaining-bar adapted to fit between said arms and provided with flanges engaging the arms behind said shoulders, a washer for holding the bar in its elevated position, a bolt for holding the washer in position, and a bolt passing through the 130

upper end of the bar and the upper arm of the side frame, substantially as set forth.

7. In a car-truck, the combination of a side frame having integral arms to receive the axle-box, and a retaining-bar adapted to fit between said arms, said arms and bar being provided with integral projections whereby

the latter is held from movement with relation to the former, substantially as described.

ERIC W. PALMQUIST.

GEORGE G. FLOYD.
